UNITED STATES PATENT OFFICE.

IRA C. TERRY, OF ST. LOUIS, MISSOURI.

CAR-TRUCK.

SPECIFICATION forming part of Letters Patent No. 270,152, dated January 2, 1883.

Application filed June 15, 1882. (No model.)

To all whom it may concern:

Be it known that I, IRA C. TERRY, of the city of St. Louis, in the State of Missouri, have invented a certain new and useful Improvement in Truck Attachments for Railway-Cars, of which the following is a full, clear, and exact description, reference being had to the accompanying drawings, forming part of this specification, and in which—

10 Figure 1 is a side elevation; Fig. 2, an end view; Fig. 3, a section on line 3 3, Fig. 6; Fig. 4, a detail side view; Fig. 5, an end view, and Fig. 6 a top view, of the truck. Fig. 7 is an enlarged detail view.

15 This invention relates to an improvement on the Letters Patent No. 228,694, issued to me 8th June, 1880; and it relates to hanging the intermediate car-truck from the bottom of the car-body in such a manner that it may have a 20 free lateral movement beneath the car.

A represents the bottom of the car-body.

B B are the end trucks, connected to the body in the usual way, and D is the intermediate truck, whose bolster E is connected to it 25 by a king-bolt, F, as usual.

G G are parallel strips, connected to the bottom of the car-body.

H H are arms pivoted to the centers of the pieces G—two on each side of the truck—and having pivoted to their other ends hangers I, 30 whose upper ends are secured to the bolster E by a pivoted connection.

Pivoted to or about the centers of the hangers I are short arms J, whose upper ends are pivoted to the stationary pieces or strips G. 35 It will thus be seen that the truck has a free lateral movement beneath the car, and that it will move on a horizontal plane.

It is evident that more than one of these intermediate trucks may be applied to the car, 40 if desired.

I claim as my invention—

The car body and truck connected by means of arms and hangers, substantially as shown and described, for the purpose set forth.

IRA. C. TERRY.
